UNITED STATES PATENT OFFICE

2,646,232

HEAD FOR SPOOL, REEL, AND WARP BEAMS

Robert V. Olson, Attleboro, Mass., assignor to
Mossberg Pressed Steel Corporation, a corpora-
tion of Massachusetts

Application November 20, 1948, Serial No. 61,291

1 Claim. (Cl. 242—123)

1

This invention relates to the head for a spool, reel beam or beamhead of the type used for reeling wire or textile material.

In the manufacture of heads for spools, reels and the like, it has been found desirable to strengthen the outer peripheral rim of the head in various ways. Where the heads are cast, different thicknesses may be obtained in the head for strengthening the same. In sheet metal heads with which this invention more particularly deals, the strengthening of the outer peripheral edge of the head has sometimes been done by flanging or curling the periphery outwardly with all thicknesses of the stock of the head remaining the same. In some cases separate pieces of material have been added to the outer peripheral rim. Several of these constructions materially add to the weight of the head which is undesirable. In some cases the outer peripheral edge of the head has been strengthened by increasing the thickness of the stock such as shown in Patent 2,286,640, dated June 16, 1942.

One of the objects of this invention is to increase the rigidity of the head, especially at the outer peripheral edge thereof, while keeping the weight of the head to the minimum.

Another object of this invention is to increase the rigidity of the head at the outer peripheral edge thereof by forming the stock in such a manner that it is formed in two plies in contiguous relation so one supports the other.

Another object of this invention is to provide a tubular section curled edge having the stock of the tube cross section extending greater than 360 degrees to provide overlapping strengthening portions either by utilizing a single ply of the stock or two plies formed together for this purpose.

With these and objects in view, the invention consists of certain novel features of construction, as will be more fully described and particularly pointed out in the appended claim.

In the accompanying drawings:

Figure 1 is a perspective view of a spool or reel constructed in accordance with this invention;

Figure 2 is an elevation partly broken away and in section showing the construction of the barrel and head;

Figure 3 is a fragmental sectional view of the edge of the head; and

Figure 4 is a fragmental sectional view illustrating a modified form of the edge of the head.

In proceeding with this invention, I form the

2

outer peripheral edge of the head in a spiral fashion so that it extends through more than 360 degrees with the portions which extend beyond the 360 degrees in contiguous relation so that one supports the other, or I may use two plies of material, such as shown in Figure 4, oppositely formed and nesting one in the other with a portion of one supporting the other, so that a two-ply relationship support is also provided.

With reference to the drawings, 10 designates the barrel which is provided with heads 11 at either end thereof. These heads have central portions extending inwardly as at 12 in end-to-end relation as at 13 with the barrel and are welded at the joint.

A center tube 14 is supported from the heads 11 by the reenforcement 15 which is bulged outwardly as at 16 and returned inwardly as at 17 to be overlapped by the ends of the center tube 14 as at 18 and secured thereto mechanically by flaring or by welding.

The outer peripheral edges 19 of the heads 11 are strengthened and made rigid by forming the stock outwardly and then inwardly into a spiral coil as at 20, so that the inner portion 21 of this coil will contact the head forming two plies of stock and a very good support for the rolled edge of the head. In effect, there is a tubular formation about the peripheral edge 30 of each of the heads which gives a very strong construction and a very rigid construction to resist bending when the spool or reel is dropped or receives a severe blow.

In some cases, as shown in Figure 4, the stock of the peripheral edge of the head 11, which is now designated as 22, is formed inwardly an extent less than that shown in Figure 2, and in this case the reenforcing plate 15 extends outwardly of the head 11 and is curled inwardly as at 23 to an extent so that its inner end 24 is in line with the plane of the reinforcing plate 15. In this manner, there is a reenforcement of the curled edge of the head 11 throughout a large portion of its extent, and a closed loop or tube 45 is provided extending around the edge of the head which provides a very rigid and strong construction.

By this arrangement, a head is formed which provides a very rigid and strong outer peripheral edge and the stock is all of the same thickness, being reenforced by double plies of the stock formed by the overlapping curls, either from a single piece of spiral formation where 55 the parts overlap beyond the 360 degree curl

or by forming the same of two plies and oppositely curling them so that the same two-ply stock is provided for reenforcing purposes.

I claim:

A metal head for a spool or reel or the like comprising a flat annular disk having a one-piece rolled outer edge spirally formed throughout an angular extent greater than 360 degrees with portions beyond the 360 degrees in contiguous relation with each other adjacent the flat plane of the disk.

ROBERT V. OLSON.
